(57) **CLAIM**

The ornamental design for a lapel microphone, as shown and described.

DESCRIPTION

FIG. 1 is a front view of a lapel microphone showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a first perspective view thereof;

FIG. 8 is a second perspective view thereof;

FIG. 9 is an exploded front view of the lapel microphone; and,

FIG. 10 is a back view thereof.

The features shown in lower opacity and the broken lines surrounding those features show portions of the lapel microphone that form no part of the claimed design.

1 Claim, 10 Drawing Sheets
